UNITED STATES PATENT OFFICE.

EDWARD J. WOOLWORTH, OF KEARNEY, NEBRASKA.

HAY-CUTTER.

1,273,975.

Specification of Letters Patent. Patented July 30, 1918.

Application filed January 21, 1916. Serial No. 73,464.

To all whom it may concern:

Be it known that I, EDWARD J. WOOLWORTH, a citizen of the United States, residing at Kearney, in the county of Buffalo 5 and State of Nebraska, have invented certain new and useful Improvements in Hay-Cutters, of which the following is a specification.

This invention relates to certain new and 10 useful improvements in hay cutters, being particularly adapted to cutting up alfalfa hay and reducing it to meal. It may also be used for reducing straw, rags, old paper, and the like, in the manufacture of straw 15 board, and other material.

The peculiarities of this invention will be hereafter described and claimed.

The object of my invention is to provide an efficient machine adapted to reduce hay, 20 especially alfalfa to that degree of fineness of marketable chopped feed which is known as alfalfa meal and to do this with the formation of a comparatively small proportion of dust and unnecessarily fine particles; also to handle effectively both the cut 25 and uncut product.

In the accompanying drawing on which like reference letters indicate corresponding parts, Figure 1 represents a plan view of a 30 machine embodying my improvements; Fig. 2 a vertical longitudinal section on the line X X of Fig. 1; Fig. 3 a left side elevation showing the main driving mechanism; and Fig. 4 a right side elevation showing the 35 return elevator for waste feed.

Referring to the drawings, the letter A designates the table of a feed box supported by the cross bars B and legs C, and provided with sides D which have slant boards 40 E to direct the entering hay into the feed mechanism. The alfalfa hay is brought in from place where it is unloaded, by a traveling belt F, or other means, which delivers it upon said table A. Above the table are 45 located a plurality of link belts G, having attachments projecting upward from the table and link belt, and located a suitable distance apart, in order to engage the feed and carry it onward, as movement is given to 50 said link belts by the several pairs of sprocket wheels H, and H', on the shaft I and I' designating the rear and front driving shafts respectively of the feed belts. The belts run in upper and lower lines connecting top and bottom of said pairs of

sprockets. Referring to Fig. 1, it will be seen that suitable openings J are left in the feed table to allow the said attachments on the link belts to pass down below the table as they reach the rearward shaft and 60 sprockets that carry the same.

It is desirable that said openings should be no larger than necessary to admit the passage downward of said attachments, on account of a tendency of the attachments to 65 catch in tangled hay and carry the same downward also. Fine particles of the alfalfa such as broken leaves, also find their way down through these openings. It is in order to avoid such waste of material, that I 70 provide a trough K, extending transversely across the feed box below the forward end of the feed table and below the said shaft I and sprockets, so that the leaves and other particles that may pass through said openings J, may be collected at the bottom of the trough, wherein is mounted a screw conveyer L, upon a shaft M, by the rotation of which, said material is transferred across the machine and delivered into the boot of an 75 elevator N, that carries it up, in the direction of the arrow, to a chute at the head of the elevator, by which the material is directed back again upon the entering feed. Thus no 80 waste occurs through the necessary openings 85 for the link belt in the feed table.

The material fed onward by the link belt and its attachments just described, is carried under a pressure feed device consisting of a feed belt preferably made of a series 90 of channel bars O, extending across the feed box from side to side, and secured to link belts mounted on sprockets P, P', carried by shafts Q and Q', designating the rear and front shafts respectively of the upper feed 95 mechanism. The shaft Q' extends across the feed box and beyond the sides thereof, supported by take-up bearings R, carried by the upper portion of said sides. The rear shaft Q, does not pass through the sides of the 100 feed box, but is mounted in boxes S, that are carried by curved pressure boards or shoes, T, which are located directly adjacent to the sides of the feed box and close to the ends of the channel bars, like fillers, and 105 extend in front of and above the front sprockets so as to keep the feed material from wedging, and are pivoted to the shaft Q', so that said shoes T, together with shaft Q, carried at the opposite end thereof, may 110

be swung upward in an arc about the shaft Q', as indicated by an arrow and dashed lines in Fig. 2. Each shoe thus acts as a spacer for the shafts Q and Q', and is curved 5 on the bottom edge as shown in Fig. 2, so as to be inclined toward and ride upon the entering hay as the hay is crowded forward by the feed belts upon the feed table and bear on the table when little or no feed material 10 is passing, so as to keep the channel bars from contact with the finger attachments of the link belts sliding along the top of the table; and by the weight of the shoes and the upper feed mechanism carried thereby, a considerable pressure is exerted upon 15 the hay, while at the same time any sudden amount of hay delivered to the table, will cause the upper feed mechanism to rise at the free end and not obstruct the passage of 20 the hay to the feed roll U, mounted on shaft V, mounted in boxes W, located in vertical pockets or guides in the housing of the feed box directly adjacent to the mill proper.

Referring particularly to Fig. 2, it will be 25 observed that the lower feed roll 2 is so located adjacent to the rearward end of the feed belt as to allow as short a space as is practical for the travel of the feed from between the feed belt and upper compression feed mechanism till its engagement by the upper and lower feed rolls; likewise said feed rolls are preferably mounted as closely as possible to the front 7 of a mill proper, which consists of a lower base portion 8 mounted upon timbers 9, carried by a suitable foundation 10, of concrete or otherwise. The mill proper has a cover which is preferably hinged to the rearward edge of the base and extends in a quadrant upward and forward to a flat top that meets the said front 7. The parting line of the cover is preferably in the horizontal plane of said hinge, and will allow of throwing the cover upward and backward about said hinge as 40 a center, by exerting sufficient upward pull upon a handle 11, by means of a tackle or otherwise. The front parting edge of the sides of said cover are shown slanting downward from the upper edge of the cover opposite the hinge, so that the sides of the cover meet the projecting sides of the front plate at the parting line 12, as shown in Figs. 2 and 3; or may be otherwise arranged to allow of the upward opening of said cover 45 to expose the base and its interior mechanism to best advantage.

Within this casing of base and cover, is mounted the mill shaft 13, carried by suitable boxes 14, and having at one end of said shaft a flywheel 15, and at the other end a pulley 16, belted to a motor or other driving means (not shown). The said pulley is connected to the mill shaft by a safety clutch which will presently be described. 50 Within the said base and cover of the

mill proper and mounted on said shaft 13, are a series of disks 22, each consisting of a hub and a serrated rim with a central plate portion which is perforated, or otherwise as desired. Upon each pair of these rims are 55 mounted a series of knives connecting said disks, and the serrations or steps of the disks are of such size as to accommodate the size of the knife U, both in width and in thickness. In the drawings, these knives are of 60 considerable width and thickness in proportion to the diameter of said disks on which they are mounted, in order that the arrangement and construction of same may be more clearly shown. 65

Referring to Fig. 1, it will be observed that the knives do not cover the whole circumference of each disk but that said knives are mounted so as to leave an alternate open space between adjacent knives, which is necessary for the passage of the air and alfalfa as it is cut; and for the proper grinding of the same in further reduction, after cutting it by the knives in their passage past a cutter 23, suitably mounted at the front opening of the mill, and directly adjacent to the path of the knives on the disks. These knives are shown in circumferential series and sections across the width of the mill, and as mounted straight or parallel to the axis of the mill shaft. This preferred sectional arrangement is to avoid the resistance of cutting along the whole edge of the cutter 23 at once, as would be the case if each knife carried by the disks was the same length as 70 that of the cutter, and parallel thereto. 75

I have found in the practical operation of a mill exemplifying these improvements, that much less dust and fine particles of hay stalks and leaves are produced, than by any other reduction mill of which I am acquainted. This uniformity of length of grinding and cutting, the one following the other, and independently of the other, produces a marketable commodity that has been received 80 with favor, and caused a demand and preference over other reductions of the same material; and the greater part of such acknowledged superiority of the meal made by my mill, is believed to be due to the construction and principles herein set forth and illustrated. 85

Referring to Fig. 2, it will be observed that the cover of the mill proper extends a considerable proportionate distance away 90 from the cutter blades on the side of the mill opposite the inlet. In this space, and substantially midway of the quadrant before mentioned, I have provided a curved plate pocket 1 extending from one side of 95 the cover to the other, having one edge secured to the said quadrant of the cover, and the other edge supported by a plate curved concentric with the axis of the shaft and adjacent to the knife blades of the disks. 100

The said curved supporting plate has its lower edge adjacent to the upper edge of the grinding cage, and forms a continuation thereof on a larger radius. This construction constitutes a pocket for the reception of stray metal that may get into the machine with the alfalfa. The curve plate portion supporting the catcher or pocket, has its upper edge approximately even with the top of the reel or circle of knife edges; and I have found by experience that the catcher is not filled up by the alfalfa meal, but that the downward current of return air through the return pipe 39, tends to clear the pocket from the meal, as indicated by the arrow in Fig. 2. It will be noted that the return pipe 39 enters the flat top of the cover in such position as to be partly over the edge of the metal catcher pocket, whereby the downward currents of air are split by the edge of said pocket, and part of them are given a rotary motion which clears out the meal that may be deposited in said pocket, thus leaving it clear for the stray metal which it is intended to catch. It will be noted that the cover is large enough above the cutting knives, to allow free space for such metal pieces to fly into the said catcher; and that the location of the catcher in the cover, allows of swinging everything out of the way when said cover is thrown back on its hinges as shown in Fig. 1, thereby giving ample space within the base for a man to have access to the knives on the disks in mounting or removing the same. Also, that the cage itself may readily be removed or repaired, or any clogging portion of metal reached by proper instrument from the underside of the cage.

Before raising the said cover, the lower section of the return pipe 39 is raised from its connection with the cover so that it telescopes the adjacent portion of the pipe, and is there held by a balance weight, cord and pulley, as indicated in Fig. 3.

The outlet pipe for the meal is preferably located between the timbers under the base of the mill, and is connected to a suitable suction fan which directs the blast of air and meal upward through the pipe 40 to the separator or dust collector (not shown). The said timbers are protected from fire by sheet iron or otherwise.

It is from this collector, that the return pipe 39 proceeds to its junction with the cover of the mill. In Fig. 2, I have shown a portion of the packing floor 41, in which floor I have mounted a conical outlet 42, provided with hinge cover 43, and having a pipe 44, leading from the cone to any part of the outlet pipe from the mill to the fan at any intermediate point that may be preferred. The cover 43 acts as a valve when closed, to prevent loss of suction effect in

the outlet pipe, but when it is raised and meal is shoveled into the said cone, the suction of the fan will take the meal down the pipe 44, and send it through its course to the packing machines again. This method of handling the meal from the packing floor is of advantage when resacking the meal; or for any other purpose in which it may be necessary or desired to handle the meal from the packing floor, either alone or with intermixture of certain desired proportions of other feed material, in providing any required percentage of different material.

Referring to Figs. 1 and 3, a suitable bracket 45 supports one end of a shaft 46, to which is keyed a sprocket 47, having a clutch face adapted to be engaged by a clutch collar 48, operated by a pivoted shift lever 49, of any convenient length, but shown in Fig. 1 for illustration, as pivoted to the said bracket. It may be extended farther to the front of the machine and be otherwise connected, according to the requirements of the operator and his preferred location with respect to the mill proper. The same applies to all levers necessary for operating the machine. This sprocket 47, is connected by a suitable link belt 50 to a countershaft or other source of power (not shown). The plan view Fig. 1, shows plainly the clutching faces have inclined teeth to give ready engagement, and adapted to be thrown out of engagement in case of excessive duty required by the entering feed. On the inside of the said shaft 46, is a pinion 51, meshing with a gear 52, mounted on the shaft of the lower feed roll 2, and having an adjacent sprocket 53, on the same shaft, connected by a link belt 105 to a similar sprocket 54, mounted on the shaft I, which also carries a gear 55, that meshes with gear 56, on a short shaft 57, on which is also mounted a sprocket 58, connected by link belt 59, with a sprocket 60, on the shaft Q', which is the driving shaft of the compression feed. On the opposite side of the feed box the shaft Q' has a sprocket 62, connected by a link belt 63, with a sprocket 64, mounted on the head-shaft 65, of the said elevator N, which carries up the overflow feed and spouts it back again on the entering alfalfa, as previously described.

The said gear 56, on the shaft 57, just referred to, also meshes with a pinion 66, Fig. 3, on the end of the conveyer shaft M, previously described as located in the bottom of the said trough K. The upper feed roll U, and its shaft V, previously described, is preferably driven from the opposite side of the mill through a sprocket 67, connected by link belt to a sprocket 68, carried by shaft 69, mounted in a suitable bracket, and also having on the same shaft a gear 70, mesh-

ing with a gear 71, mounted on the end of the lower feed roll shaft 72, by which means the lower roll is driven reversely from the upper feed roll.

5 Referring again to the return elevator N, Fig. 4, it will be observed that the head shaft is provided with bearings having wide flanges 73, fitting snugly against the sides of the elevator box, while the bearings themselves are adapted to slide in slots in the sides of said box or trough. Each of said flanges 73, has a hook rod 74 engaging a perforation in the flange and extending out the upper end of the trough, where it is provided with an adjusting nut threaded thereon, whereby the head shaft may be drawn up to take up the slack or stretch of the elevator belt. The flanges cover the slots in the sides. In place of said elevator, other means may be employed to transfer the said overflow waste portions of feed from the trough K upward, and upon the entering feed.

Referring to Fig. 4, the carrier F, before mentioned as passing over the rear pulley on the shaft 75, is preferably driven by a sprocket 76, on said shaft, connected by link belt 77, with a sprocket 78, carried by the forward shaft I', previously mentioned in connection with the feed belts and attachments passing over the table A.

The improvement and advantage of cutting knives made and attached as described, in connection with the cutter bar and adjacent screen, is that they do away with the massing, of the uncut pieces of alfalfa or other material at one side of the machine, which would be the tendency with spiral knives set at a considerable twist or continuous inclination to the cutter bar along their whole length, or width of the machine.

Having thus fully described my invention, what I claim as new and desire to secure by Letters Patent, is:

45 1. In a machine of the character described, the combination with a rectangular base portion, a cover having a flat top and a quadrant back and hinged to said base portion, of a shaft mounted in said casing, cutting 50 blades mounted on said shaft, a cutter therefor, a catcher consisting of a curved plate pocket, secured to the upper rear portion of said cover and provided with a curved front support concentric with said shaft, and a 55 grinding cage below the hinge concentric

with said shaft, substantially as and for the purpose described.

2. A machine of the character described, comprising a rectangular base portion, a hinged cover, a curved pocket located within said cover and at one side thereof, a return air pipe in the top of the cover projecting partly over said pocket, whereby said pocket is cleared for the reception of metal that may enter the machine.

3. A mill of the character described comprising a casing, a shaft mounted therein, a cutter bar, and a cutter thereon inclined to the axis of said shaft, a plurality of blade supports fixed on said shaft, a plurality of 70 series of straight cutting blades mounted on said blade supports parallel to said shaft, and arranged in short sections horizontally and by steps circumferentially in adjacent series, and means to adjust said blades, substantially as described.

4. The combination with a mill of the character described having a discharge outlet, an exhaust fan adapted to draw by suction the discharge from said mill, and pipes 80 leading from the center of said fan to the mill outlet and from the discharge of said fan to the packing floor, of an auxiliary pipe leading from the packing floor, having a covered hopper at one end to maintain the 85 suction effect and connected with said discharge pipe from the mill on the suction side of said fan, substantially as shown and described.

5. In a mill of the character described, the 90 combination with a feed table having holes transversely located near the mill, and a traveling feed device arranged to pass along above said table and down through the holes therein, whereby the smaller particles of 95 feed are likewise carried down through said holes, of a transverse conveyer located below the holes in said table to catch the feed particles, and an elevator located at the side of said table with its boot below the said 100 conveyer, and provided with a delivery spout near the upper end extending over said table, substantially as shown and described.

In testimony whereof I have affixed my 105 signature in presence of two witnesses.

EDWARD J. WOOLWORTH.
